UNITED STATES PATENT OFFICE

159,569

TOOTHERBRUSH

John Yourek, Chicago, Ill.

Application February 21, 1950, Serial No. 8,046

Term of patent 14 years

(Cl. D9—2)

To all whom it may concern:

Be it known that I, John Yourek, a citizen of the United States, residing at Chicago, in the county of Cook and State of Illinois, have invented a new, original, and ornamental Design for a Tooth Brush, of which the following is a specification, reference being had to the accompanying drawing, forming part thereof.

In the drawing:

Fig. 1 is a view in side elevation of a tooth brush, showing my new design.

Fig. 2 is a plan view of the tooth brush shown in Fig. 1.

Fig. 3 is a view of the reverse side of the tooth brush shown in Fig. 2.

Fig. 4 is a view of the tooth brush shown in Figs. 1 and 2 in end elevation, taken from the bristle end, and,

Fig. 5 is an end view of the tooth brush taken from the handle end.

I claim:

The ornamental design for a tooth brush, as shown.

JOHN YUREK.
